(57) **CLAIM**

The ornamental design for a portable photo booth, as shown and described.

DESCRIPTION

FIG. 1 is a front perspective view of a portable photo booth;
FIG. 2 is a front view of the portable photo booth;
FIG. 3 is a rear view of the portable photo booth;
FIG. 4 is a left view of the portable photo booth;
FIG. 5 is a right view of the portable photo booth;
FIG. 6 is a bottom view of the portable photo booth; and,
FIG. 7 is a top view of the portable photo booth.

The broken lines depict portions of the portable photo booth in which the design is embodied and form no part of the claimed design.
